US00D649589S

(12) **United States Design Patent**
Clegg et al.

(10) **Patent No.:** US D649,589 S
(45) **Date of Patent:** ** Nov. 29, 2011

(54) **VIDEO INSERT**

(75) Inventors: **Timothy P. Clegg**, Manhattan Beach, CA (US); **Michael D. Ronk**, Lawndale, CA (US)

(73) Assignee: **Americhip, Inc.**, Los Angeles, CA (US)

(**) Term: **14 Years**

(21) Appl. No.: **29/397,900**

(22) Filed: **Jul. 22, 2011**

Related U.S. Application Data

(60) Division of application No. 29/385,685, filed on Feb. 17, 2011, now Pat. No. Des. 643,060, which is a continuation of application No. 29/368,492, filed on Aug. 24, 2010, which is a continuation of application No. 29/363,762, filed on Jun. 14, 2010, now Pat. No. Des. 629,459, which is a continuation of application No. 12/413,343, filed on Mar. 27, 2009, now Pat. No. 8,011,122, which is a continuation of application No. 12/263,277, filed on Oct. 31, 2008, which is a continuation of application No. 12/199,740, filed on Aug. 27, 2008, now abandoned.

(57) **CLAIM**

The ornamental design for a video insert, as shown and described.

DESCRIPTION

FIG. 1 is a perspective view of an embodiment of the present invention;

FIG. 2 is a top plan view of the present invention shown in FIG. 1;

FIG. 3 is a left side elevational view of the present invention shown in FIG. 1;

FIG. 4 is a right side elevational view of the present invention shown in FIG. 1;

FIG. 5 is a bottom plan view of the present invention shown in FIG. 1;

FIG. 6 is a top elevational view of the present invention shown in FIG. 1;

FIG. 7 is a bottom elevational view of the present invention shown in FIG. 1;

FIG. 8 is a perspective view of a second embodiment of the present invention;

FIG. 9 is a top plan view of the present invention shown in FIG. 8;

FIG. 10 is a left side elevational view of the present invention shown in FIG. 8;

FIG. 11 is a right side elevational view of the present invention shown in FIG. 8;

FIG. 12 is a bottom plan view of the present invention shown in FIG. 8;

FIG. 13 is a top elevational view of the present invention shown in FIG. 8;

FIG. 14 is a bottom elevational view of the present invention shown in FIG. 8;

FIG. 15 is a perspective view of a third embodiment of the present invention;

FIG. 16 is a top plan view of the present invention shown in FIG. 15;

FIG. 17 is a left side elevational view of the present invention shown in FIG. 15;

FIG. 18 is a right side elevational view of the present invention shown in FIG. 15;

FIG. 19 is a bottom plan view of the present invention shown in FIG. 15;

FIG. 20 is a top elevational view of the present invention shown in FIG. 15; and,

FIG. 21 is a bottom elevational view of the present invention shown in FIG. 15.
